MULTIPLE STAGE WATER HEATER

Norton B. Leo, deceased, late of Yonkers, N. Y.,
by Charlotte E. Leo, administratrix, Tuckahoe,
N. Y.

Application August 3, 1940, Serial No. 351,653

2 Claims. (Cl. 122—18)

This invention relates to liquid heaters, and more particularly to multiple stage heaters, wherein a quantity of water is maintained at a high temperature at all times.

In the usual "storage" hot water heater, all of the water in the container or tank is at a high temperature and the cost of maintaining this large body of water at such a high temperature at all times is considerable. Such devices, though well insulated, lose a great amount of heat through radiation. The present device overcomes these objections with a simple and commercially practical construction.

It is among the desiderata of the invention to provide a water heater, wherein a comparatively small proportion of the liquid is kept at the high temperature necessary for use, while the remainder is at a gradually increasing temperature and is heated largely by the heat lost to the small highly heated portion.

Another object of the invention is to provide a more efficient system of heating a body of liquid and for keeping said liquid at a constant temperature.

A further object is to so arrange the heater, that certain portions of the liquid may be at higher or lower temperatures than other portions without the use of separate tanks or containers of the usual "economizer" type.

An important object of the present invention is to provide a means for circulating the liquid in the heater, without mechanical moving parts.

Other objects and advantages of the invention will be in part obvious and in part pointed out hereinafter.

A preferred embodiment of the invention is disclosed in the accompanying drawing, wherein

Fig. 1 is a vertical sectional view of the invention.

Fig. 2 is a fragmentary section through one of the heating units.

A liquid container or tank 1 is provided of substantially cylindrical design, having the usual insulation 2 and outer jacket or cover 3. Immediately below the tank, a space is provided for the burners 4 and 4' which are arranged in a manner to be later described. A flue space 5 may surround the lower portion of the tank 1 in order to absorb the fullest possible amount of heat from the gases of combustion.

Arranged below and in communication with the tank 1 are a series of water heater pipes 6, 7 and 8. These pipes are part of a system whereby several layers of liquid may be maintained at the desired temperature and each layer may be

heated independently of every other layer, except that the upper layer must be at a higher temperature than the next lower layer, and this in turn must be heated more than the next layer, etc.

In order to permit this "layer heating" arrangement the circulating heater pipe 6 comprises a vertical intake pipe 9 serving as a conduit from the lowermost part of the upper or "hottest" layer of the liquid. This pipe 9 feeds the lower end of the sloping heater pipe 6 which, at its upper end is in communication with a vertical return pipe 10, which in turn opens to the upper part of said "hottest" layer of liquid. Thus, in effect, a continuous stream of liquid is withdrawn from the tank, heated and returned.

Similarly, a heater pipe 7 is provided with the vertical intake pipe 11 from the lower part of the middle layer, and a return pipe 12 to the upper part. The intake pipe 13, and return pipe 14, are arranged in the lower layer with the heater pipe 8 to form the third unit.

From the foregoing it will be seen that any of these circulating units may be heated independently, or all may be heated simultaneously. Likewise, various well known control devices may be used in conjunction therewith, to effect the result desired. A preferred method would be to provide a bimetallic thermal control so arranged to cause operation of the burners 4 and 4' whenever cold water is flowing into the tank through the inlet pipe 15, or when hot water is being drawn through the outlet pipe 15'. While a second thermal device 21 would be affected by the temperature of the upper or "hottest" layer to cause operation of the individual burner 4', or the burners 4 and 4'.

In order to obtain the most efficient operation, each of the return pipes 10, 12 and 14 are provided at their lower ends, in close proximity to the bottom of the tank 1, with "heat pumps" 16. These consist of jets 17, arranged to discharge the heated liquid from the heater pipes 6, 7 and 8, through Venturi tubes 18, which are connected at their upper ends to the return pipes 10, 12 and 14, and at their lower ends are open at 19 to the interior of the tank 1 immediately above the bottom thereof.

As the pipes 10, 12 and 14 are inclined upward 50 toward the "heat pumps," operation of the burners will cause a strong flow through the jets 17 and by their action the venturis 18 will draw liquid from near the bottom of the tank 1, and thus cause circulation across the bottom, prevent the formation thereon of vapor bubbles, and

permit the liquid to come into direct contact with the heated bottom of the tank, in order to obtain more efficient operation. This will also cause general circulation of the liquid to supplement the localized circulation created by the heater pipes 6, 7 and 8.

In some instances it has been found advisable to provide a baffle plate 22, in proximity to the bottom of the tank 1, to restrict the area through which liquid may flow to the openings 19 of the venturis 18. In such a construction the heated liquid will be drawn across the surface of the bottom of the tank 1 and while it will not be heated as much as the liquid flowing through the heater pipes 6, 7 and 8, it will absorb considerable heat. Referring to the drawing, it will be seen that the baffle plate 22 extends nearly to the sides of the tank 1, and is then extended upward. This feature causes the heated fluid adjacent that portion of the walls of the tank 1, heated by the flue gases to be the first to be drawn to the space between the bottom of said tank and the baffle 22.

Therefore, it will be seen, that the various steps in heating the system constitute a multiplicity of stages, each one of which is a "pre-heat" for the following one. In this way, every possible advantage is secured in arranging an efficient and economical water heater.

While there has been shown and described one embodiment of the invention, it should be understood that many variations and changes may be made without departing from the invention, and such modifications as come within the scope of the appended claims, are considered within the spirit of the invention.

What is claimed is:

1. A liquid heater comprising a container, a

conduit having both of its ends opening into the container at the lower part thereof, another conduit having both of its ends opening into the container at the upper part thereof, each of said conduits comprising two portions, one portion having a terminal nozzle formation directed into the other portion, the junction of the two portions of each conduit in the region of said nozzle being open to receive liquid from the interior of the container, the portion of each of said conduits which has the nozzle formation thereon being subjected to high heat whereby an ejector action will be created at said nozzle junction to stimulate circulation of liquid within the container, means for supplying fresh liquid to the container, and means for withdrawing liquid from the container.

2. A liquid heater comprising a container, a baffle plate in close proximity to the bottom of the container, a plurality of return pipes opening through said baffle plate and extending upwardly to different heights within the container, a plurality of heater pipes, one associated with each of said return pipes and each having a portion lying outside the container to be subjected to high heat, each of said heater pipes having a nozzle at one end directed into the lower end of its associated return pipe, the junction at each nozzle being open into the space between said baffle plate and the bottom of the container, the other end of each of said heater pipes opening into the container at a level corresponding to the level at which the associated return pipe opens into the container, means for supplying fresh liquid to the container and means for withdrawing liquid from the container.
